UNITED STATES PATENT OFFICE.

CHARLES W. SMITH, OF NORWALK, OHIO.

DESIGN FOR A CURTAIN-POLE BRACKET.

SPECIFICATION forming part of Design No. 24,108, dated March 12, 1895.

Application filed February 9, 1895. Serial No. 537,833. Term of patent 7 years.

To all whom it may concern:

Be it known that I, CHARLES W. SMITH, a citizen of the United States, residing at Norwalk, in the county of Huron and State of Ohio, have invented a certain new and useful Design for Curtain-Pole Brackets; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 Figure 1 is a side elevation of a curtain pole bracket embodying my design, and Fig. 2 is a cross section on the line x, x of Fig. 1.

My design has reference to brackets for curtain poles, the special features of which being 20 the annular pole supporting portion A having the double convex surfaces a, a , terminating in a ridge A', and provided with a central perforation B. The cylindrical wall engaging portion is flattened on one side at C, and at 25 its middle is the bead D having convex sur-

faces, the outwardly flaring concaved portions E extending from the ridges e , and terminating at their greatest diameter in the ridges F, and at the points E' and E' have contact with the ridge A' of the annular ring 30 A. From the ridges F are the outwardly extending convex surfaces G terminating in recesses g adjoining which are the outwardly flaring convex surfaces J terminating in ridges K from which outwardly extend the 35 concave portions L adjoining the substantially cylindrical sections M terminating in convex globular portions K each having concaved tapering surfaces O, and provided each with a blunt conical point R. 40

What I claim is—

The design for a curtain pole bracket as herein shown and described.

In testimony whereof I affix my signature in presence of two witnesses.

CHARLES W. SMITH.
